UNITED STATES PATENT OFFICE.

LORENZO D. CORSER, OF BRIDGETON, MAINE.

COW-TAIL HOLDER.

SPECIFICATION forming part of Letters Patent No. 562,379, dated June 23, 1896.

Application filed October 5, 1895. Serial No. 564,773. (No model.)

To all whom it may concern:

Be it known that I, LORENZO D. CORSER, a citizen of the United States, residing at Bridgeton, in the county of Cumberland and State 5 of Maine, have invented a new and useful Cow-Tail Holder, of which the following is a specification.

The purpose of the present invention is to provide a simple and effective means for securing the cow's tail during the process of milking, thereby avoiding the annoyance and inconvenience experienced when the tail is permitted to switch and flirt about. Devices of this character as heretofore constructed 15 do not grip the tail securely and cannot be readily and easily applied, and these objectionable features are avoided by the present invention, which provides an appliance that can be fitted to and will securely grip and 20 hold the animal's tail to the ease and comfort of the milker.

The invention consists, essentially, of a jointed frame having a clasp adjacent to the joint and formed of similar members which 25 move with the respective parts of the frame and are operated thereby.

The improvement also consists in the novel features and the peculiar construction and combination of the parts which hereinafter 30 will be more particularly set forth, illustrated, and specifically claimed.

In the accompanying drawings is illustrated an adaptation of the invention, although changes in the form, proportion, and 35 the minor details of construction may be resorted to without departing from the principle or sacrificing any of the advantages of this invention.

In the said drawings, Figure 1 shows the invention applied. Fig. 2 is a perspective view of the device as it will appear when placed upon the market. Fig. 3 is a detail view of the jointed ends, showing them disconnected.

The same reference-numerals denote corresponding and like parts in all the figures of the drawings, and in the latter 1 indicates the jointed frame, and 2 the cord or rope by means of which the device is retained in place when properly fitted upon the animal. This cord 45 or rope is secured in any desired manner to one end of the frame, and the opposite end 50 portion of the cord is rove through a series

of openings 3 at the opposite end of the frame, so as to admit of the cord being lengthened or shortened to adapt the device to different-sized animals. The cord is rove through the series of openings 3 in such a manner as to prevent its slipping after being properly adjusted.

The frame is composed of similarly-formed parts 4, which are hinged together at their inner ends, and which curve symmetrically to conform to the rump of the animal. A clasp is formed opposite to the hinged parts on the concaved side of the frame, and comprises similar members 5, which are approximately of semicircular shape and which unitedly form a substantially circular fetter to encircle the cow's tail. The free ends of the members 5 butt together and limit the closing 65 of the parts 4. Each part 4 will be provided with a member 5, which may be applied thereto in any convenient manner; but for the sake of simplicity and economy of construction the members 5 form an integral part of 70 the respective frame-sections and are provided by recurving or folding a portion of the parts 4 upon themselves, as shown most clearly in Fig. 3, and the folds are opened 75 sufficiently to provide for the reception of the pivot 6, by means of which the hinge-joint is had between the parts of the frame. By having the clasp disposed on the inner or concaved side of the jointed frame it will occupy a position opposite the space formed between the 80 buttocks and thereby be out of the way and assist in retaining the device in proper position.

Having thus described the invention, what is claimed as new is—

1. A cow-tail holder comprising a frame curving in its length and formed of similar parts which are hinged together at their inner ends, and having extensions projecting inward from the concave side of the frame 85 contiguous to the hinge-joint and oppositely curving to unitedly form a fetter or clasp whose passage is parallel with the said hinge-joint so as to encircle the cow's tail, substantially as described.

2. A cow-tail holder consisting of a frame formed of similar parts hinged together, a clasp or fetter opposite the hinge-joint comprising approximately semicircular members

carried by and movable with the respective parts of the frame, and inclosing a space parallel with the said hinge-joint and adapted to encircle the cow's tail, and means for securing the device to the animal, substantially in the manner set forth.

In testimony that I claim the foregoing as

my own I have hereto affixed my signature in the presence of two witnesses.

LORENZO D. CORSER.
